UNITED STATES PATENT OFFICE.

WILLIAM L. TOBEY, OF WINTHROP, MASSACHUSETTS.

MUFFLING DEVICE.

1,048,111.

Specification of Letters Patent. Patented Dec. 24, 1912.

Application filed August 15, 1912. Serial No. 715,235.

To all whom it may concern:

Be it known that I, WILLIAM L. TOBEY, a citizen of the United States, residing in Winthrop, county of Suffolk, and State of Massachusetts, have invented an Improvement in Muffling Devices, of which the following description, in connection with the accompanying drawings, is a specification, like letters on the drawings representing like parts.

This invention relates to a device for muffling the exhaust of internal combustion engines or motors, and more particularly those used in motor boats.

15. The invention has for its object to provide a simple, efficient and inexpensive device for the purpose specified.

To this end, the muffler consists of a casing or shell which is preferably spherical in form and is provided with a gas inlet and a gas outlet, preferably located substantially at right angles to each other, with the gas inlet located near the circumference of the casing and substantially at a tangent thereto and with the gas outlet located at or near the center of the casing, whereby the gases which enter the casing may be given a rotary motion which is substantially reduced at the center of the casing, so that the gases may issue from the casing with substantially little noise.

Provision is made for regulating or adjusting the passage of the gases out of the casing as will be described and also for reducing the temperature of the gases.

These and other features of this invention will be pointed out in the claims at the end of this specification.

Figure 1: is an elevation of a device embodying this invention. Fig. 2, a section on the line 2—2, Fig. 1, and Fig. 3, a section on the line 3—3, Fig. 2.

Referring to the drawings, *a* represents a hollow casing or shell, which is preferably spherical in form and is provided near its circumference with a gas inlet *b*, which is extended from the spherical casing substantially at a tangent thereto, so that the gases discharged into the casing from the motor (not shown) may have imparted to them a rotary motion within the casing, from which they pass in a substantially quiet state

through an outlet located near the center of the casing substantially at right angles to the inlet *b*. In the present instance, the gas outlet for the casing *a* is formed by pipe *c*, which engages a threaded opening in a boss *d* on the said casing, and is adjustably extended into the latter to near its center as represented in Fig. 2; said pipe being open at its inner end for the passage of the gases into the same from the casing. By reference to Figs. 1 and 3, it will be seen that the gases pass out of the casing at the point within the latter, where the velocity of the gases is materially reduced and also pass out from the casing in a direction substantially at right angles to the path of rotation of the gases within the casing, and as a result, the gases are muffled down so that they may be discharged from the outlet pipe *c* into the air without objectionable noise.

Provision is made for insuring a continuous flow of the gases out of the casing *a*, and in the present instance this result is obtained by a threaded pipe 10, which is extended into the casing through a threaded opening in a boss 12 located substantially diametrically opposite to the threaded boss *d*.

The pipe 10 is capable of being adjusted toward or from the open inlet end of the outlet pipe *c* and practically forms a valve for regulating the passage of the gases from the casing into the outlet pipe *c*. The pipe 10 is closed at its outer end by a cap 13 and may be secured in its adjusted position by the nut 14 coöperating with the boss 12.

By reference to Fig. 2, it will be seen that the ends of the pipes *c*, 10, are separated by a space 15, through which the gases pass from the casing *a* into the outlet pipe *c*, and that the quantity or volume of the gases which passes to the outlet pipe may be varied by adjusting the pipe 10 so as to increase or decrease the width of the space 15. The threaded openings in the bosses *d*, 12, are preferably of the same diameter or size, so that the position of the pipes *c*, 10, may be reversed from that shown in Fig. 2, to enable the outlet pipe *c* to be easily led to a convenient point of discharge. Provision may be made for cooling the muffler, and to this end, the casing *a* is provided with a water inlet pipe 20 located at the top of

the casing as herein shown, and so as to discharge the water into the path of the hot incoming gases. The casing *a* is provided with a water outlet pipe 21 located substantially diametrically opposite to the water inlet pipe 20, through which the water may pass out of the casing. With mufflers employed on motor boats, it is preferred to use the water inlet and outlet pipes 20, 21, but it is not desired to limit the invention in this respect. The casing *a* has its gas inlet *b* connected with the exhaust pipe 23 for the motor, and the water inlet pipe 20 connected with a suitable source of supply, as, for instance, a water pump (not shown), and in operation, the hot exhaust gases from the motor are discharged into the casing *a*, and by reason of the tangential location of the inlet *b* are given a rotary motion within the casing *a* and pass through the space 15 into the outlet pipe *c*, from which they may discharge into the atmosphere in a substantially noiseless manner. The exhaust gases enter the muffler substantially hot and may have their temperature reduced materially by the water admitted into the casing through the pipe 20, so that the hand may be laid onto the casing without danger of being burned.

30 The parts of the device may be made of iron or other metal, and require very little labor to put them into condition to assemble. The device can be produced at a minimum expense and is practically indestructible as there are no parts liable to get out of order.

Claims.

1. In a device of the character described, in combination, a hollow casing substantially spherical in form, and provided with an inlet opening arranged substantially at a tangent to the circumference of said casing to impart to the exhaust gases a rotary motion within the casing and with an outlet opening substantially at right angles to said inlet opening, and an outlet pipe for said casing extended thereinto from said outlet opening toward and near to the center of the casing and into the exhaust gases in their quietest state, for the purpose specified.

2. In a device of the character described, in combination, a hollow casing substantially spherical in form and provided with an inlet opening arranged substantially at a tangent to the circumference of said casing and with an outlet opening substantially at right angles to said inlet opening, an outlet pipe for said casing extended thereinto from said outlet opening toward the center of the casing, and a device in line with said outlet pipe and extended through said casing at a point substantially diametrically opposite to said outlet pipe, said device being adjustable from outside of the casing toward

and from the inlet end of said outlet pipe, 65 for the purpose specified.

3. In a device of the character described, in combination, a hollow casing substantially spherical in form and provided with a gas inlet opening arranged substantially at 70 a tangent to the circumference of said casing and with a gas outlet opening substantially at right angles to said gas inlet, and having a water inlet opening arranged in the vicinity of the gas inlet to admit water 75 into the casing and cause it to meet the incoming gases, and having a water outlet opening, and a gas outlet pipe extended into said casing from the gas outlet opening toward the center of the casing, substantially as described.

4. The combination with the exhaust pipe of an internal combustion motor, of a hollow casing having an inlet opening connected with said exhaust pipe and arranged to 85 direct the exhaust gases into the casing to impart to them a rotary movement within the casing and having an outlet for said gases arranged substantially at right angles to said gas inlet and extended into the casing toward the center thereof and into the quietest zone of said gases, said outlet pipe being open at its end within the casing, substantially as described.

5. In a device of the character described, 95 in combination, a hollow casing having openings substantially at right angles to each other, one of said openings being arranged to direct incoming gases into the casing to impart to them a rotary movement 100 within the casing, and the other of said openings being located substantially at right angles to the first-mentioned opening, and a pipe extended through said second opening into the casing and toward the center thereof and open at its inner end to receive the gases from the center of the rotary movement of the same.

6. In a device of the character described, in combination, a hollow casing provided 110 with an inlet opening and with an outlet opening, and a device supported by the wall of the casing opposite to said outlet opening and extended into said casing and movable bodily therein toward and from 115 said outlet opening to regulate the passage of the gases out of said casing.

7. In a device of the character described, in combination, a hollow casing provided with an exhaust inlet opening and with an 120 exhaust and provided with a water inlet and a water outlet, and means for regulating the discharge of the exhaust from said casing through said exhaust outlet.

8. In a device of the character described, 125 in combination, a hollow casing provided with an exhaust inlet opening and with an exhaust outlet opening, an exhaust pipe

open at its inner end and extended through said exhaust outlet opening into said casing, and a device carried by said casing and extended therein and adjustable toward and from said outlet pipe and coöperating with the opening therein to regulate the passage of the gases from the casing into the exhaust pipe, for the purpose specified.

In testimony whereof, I have signed my name to this specification in the presence of 10 two subscribing witnesses.

WILLIAM L. TOBEY.
